ABSTRACT

A new and distinct cultivar of *Petunia* plant named 'Dopetsurage21', characterized by its relatively compact, upright and mounding to hanging plant habit; moderately vigorous growth habit; freely branching habit; early and freely flowering habit; large light purple-colored flowers with purplish red-colored venation and dark purple-colored throats; and good garden performance.

1 Drawing Sheet

1

Botanical designation: *Petunia X hybrida*.
Cultivar denomination: 'DOPETSURAGE21'.

**STATEMENT REGARDING PRIOR
DISCLOSURES BY INVENTOR/APPLICANT &
ASSIGNEE**

An European Community Plant Breeder's Rights application for the instant plant was filed by the Applicant/Assignee, Dümmen Group B.V. of De Lier, The Netherlands on Aug. 19, 2020, application number 2020/1950. Foreign priority is not claimed to this application.

The Inventor and Applicant/Assignee assert that no publications nor advertisements relating to sales, offers for sale or public distribution occurred more than one year prior to the effective filing date of this application. Any information about the claimed plant would have been obtained from a direct or indirect disclosure from the Inventor and/or Applicant/Assignee. Inventor and Applicant/Assignee claim a prior art exception under 35 U.S.C. 102(b)(1) for disclosure and/or sales prior to the filing date but less than one year prior to the effective filing date.

BACKGROUND OF THE INVENTION

The present invention relates to a new and distinct cultivar of *Petunia* plant, botanically known as *Petunia X hybrida* and hereinafter referred to by the name 'Dopetsurage21'.

The new *Petunia* plant is a product of a planned breeding program conducted by the Inventor in Rheinberg, Germany. The objective of the breeding program is to create new compact, freely branching and early-flowering *Petunia* plants with numerous attractive flowers.

The new *Petunia* plant is a naturally-occurring whole plant mutation of a proprietary selection of *Petunia X hybrida* identified as code number TT14-007140-002, not patented. The new *Petunia* plant was discovered and

2

selected by the Inventor as a single flowering plant from within a population of plants of the mutation parent selection in a controlled greenhouse environment in Rheinberg, Germany in May, 2020.

5 Asexual reproduction of the new *Petunia* plant by terminal vegetative cuttings in a controlled greenhouse environment in Rheinberg, Germany since June, 2020 has shown that the unique features of this new *Petunia* plant are stable and reproduced true to type in successive generations.

SUMMARY OF THE INVENTION

Plants of the new *Petunia* have not been observed under all possible combinations of environmental conditions and 15 cultural practices. The phenotype may vary somewhat with variations in environmental conditions such as temperature and light intensity without, however, any variance in genotype.

The following traits have been repeatedly observed and 20 are determined to be the unique characteristics of 'Dopetsurage21'. These characteristics in combination distinguish 'Dopetsurage21' as a new and distinct *Petunia* plant:

- 25 1. Relatively compact, upright and mounding to hanging plant habit.
2. Moderately vigorous growth habit.
3. Freely branching habit.
4. Early and freely flowering habit.
5. Large light purple-colored flowers with purplish red-colored venation and dark purple-colored throats.
6. Good garden performance.

Plants of the new *Petunia* can be compared to plants of the mutation parent selection. In side-by-side comparisons, plants of the new *Petunia* differ primarily from plants of the mutation parent selection in flower color as flowers of plants of the new *Petunia* are light purple in color whereas flowers of plants of the mutation parent selections are white in color.

Plants of the new *Petunia* can be compared to plants of *Petunia X hybrida* 'Kesupite', not patented. In side-by-side comparisons, plants of the new *Petunia* and 'Kesupite' differ primarily in the following characteristics:

1. Plants of the new *Petunia* are more compact than plants of 'Kesupite'. 5
2. Plants of the new *Petunia* are more upright than and not as trailing as plants of 'Kesupite'.
3. Plants of the new *Petunia* have smaller leaves than plants of 'Kesupite'.
4. Plants of the new *Petunia* have larger flowers than plants of 'Kesupite'. 10
5. Flowers of plants of the new *Petunia* are light purple in color whereas flowers of plants of 'Kesupite' are white in color. 15

BRIEF DESCRIPTION OF THE PHOTOGRAPH

The accompanying colored photograph illustrates the overall appearance of the new *Petunia* plant showing the colors as true as it is reasonably possible to obtain in colored reproductions of this type. Colors in the photograph may differ slightly from the color values cited in the detailed botanical description which accurately describe the colors of the new *Petunia* plant. The photograph is a side perspective view of a typical flowering plant of 'Dopetsurage21' grown in a container. 20

DETAILED BOTANICAL DESCRIPTION

The aforementioned photograph and following observations, measurements and values describe plants grown during the spring in 22-cm containers in a glass-covered greenhouse in Rheinberg, Germany and under cultural practices typical of commercial *Petunia* production. During the production of the plants, day and night temperatures averaged 18° C. and light levels averaged 4,500 lux. Plants were twelve weeks old when the photograph was taken and 25 weeks old when the description was taken. In the following description, color references are made to The Royal Horticultural Society Colour Chart, Fifth Edition, 2007, except where general terms of ordinary dictionary significance are used. 25

Botanical classification: *Petunia* X *hybrida* 'Dopetsurage21'.

Parentage: Naturally-occurring whole plant mutation of a proprietary selection of *Petunia X hybrida* identified as code number TT14-007140-002, not patented.

Propagation:

Type.—By terminal vegetative cuttings.

Time to initiate roots, summer.—About five days at temperatures about 20° C.

Time to initiate roots, winter.—About seven days at temperatures about 20° C.

Time to produce a rooted young plant, summer.—55 About three weeks at temperatures about 20° C.

Time to produce a rooted young plant, winter.—About four weeks at temperatures about 20° C.

Root description.—Fine, fibrous; close to 155B in color, actual color of the roots is dependent on substrate composition, water quality, fertilizers, substrate temperature and age of roots.

Rooting habit.—Freely branching; dense.

Plant description:

Plant and growth habit.—Relatively compact, upright and mounding to hanging plant habit; freely branch-

ing habit with about ten primary lateral branches each with about eleven secondary branches developing after pinching; moderately vigorous growth habit; moderate growth rate.

Plant height, soil level to top of foliar plane.—About 19.5 cm.

Plant height, soil level to top of floral plane.—About 21 cm.

Plant diameter.—About 70 cm.

10 *Lateral branch description*:

Length.—About 44 cm.

Diameter.—About 5 mm.

Internode length.—About 2.2 cm.

Strength.—Moderately strong.

Aspect.—Initially upright to outwardly spreading.

Texture and luster.—Pubescent; semi-glossy.

Color, developing.—Close to 144B.

Color, fully developed.—Close to 144A.

Leaf description:

Arrangement.—Before flowering, alternate; after flowering, opposite; simple.

Length.—About 3.6 cm.

Width.—About 1.5 cm.

Shape.—Spatulate.

Apex.—Obtuse.

Base.—Attenuate.

Margin.—Entire.

Texture and luster, upper and lower surfaces.—Pubescent; leathery; semi-glossy.

Venation pattern.—Pinnate; arcuate.

Color.—Developing leaves, upper surface: Close to 137C. Developing leaves, lower surface: Close to 147B. Fully expanded leaves, upper surface: Close to 137A; venation, close to 144B. Fully expanded leaves, lower surface: Close to 147B; venation, close to 144B.

Petioles.—Length: About 3 mm. Diameter: About 2 mm. Strength: Moderately strong; firm. Texture and luster, upper and lower surfaces: Smooth, glabrous; matte. Color, upper and lower surfaces: Close to 144B.

Flower description:

Flower type and flowering habit.—Single salverform flowers arising from leaf axils; freely flowering habit with usually about 444 flowers and flower buds developing per plant; flowers face mostly upright to outwardly.

Fragrance.—None detected.

Natural flowering season.—Plants flower continuously during the spring and summer in Germany; early flowering habit, plants typically beginning flowering about nine weeks after planting.

Flower longevity.—Individual flowers last about two to three days on the plant; flowers persistent.

Flower buds.—Length: About 3.8 cm. Diameter: About 7.3 mm. Shape: Ovoid. Texture and luster: Rippled; semi-glossy. Color: Proximally, close to 144C and distally, close to N77B.

Flower diameter.—About 6.7 cm.

Flower depth (height).—About 4.1 cm.

Flower throat diameter.—About 1.3 cm.

Flower tube length.—About 2.7 cm.

Flower tube diameter, proximally.—About 9.3 mm.

Corolla.—Arrangement: Five petals fused at the base and opening into a flared trumpet. Petal lobe length

US PP33,730 P2

5

(from throat): About 4.4 cm. Petal lobe width: About 3.2 cm. Petal shape: Roughly spatulate. Petal apex: Obtuse. Petal margin: Entire; slightly undulate. Petal texture and luster, upper and lower surfaces: Rippled, glabrous; semi-glossy. Throat texture and luster: Rippled, glabrous; semi-glossy. Tube texture and luster: Rippled, pubescent; semi-glossy. Color: Petal lobe, when opening, upper surface: Close to 77C. Petal lobe, when opening, lower surface: Close to 75B. Petal lobe, fully opened, upper surface: Close to 75A; venation, close to 71B; color becoming closer to 76D with subsequent development. Petal lobe, fully opened, lower surface: Close to 75C; venation, close to 144C; color becoming closer to 76D with subsequent development. Flower throat: Close to N79C; venation, close to 71A. Flower tube: Close to N77D; venation, close to 197A.

5

Sepals.—Arrangement: Five sepals fused at the base forming a tubular star-shaped calyx. Length: About 1.7 cm. Diameter: About 2.8 mm. Shape: Oblong. Apex: Rounded. Base: Decurrent. Margin: Entire. Texture and luster, upper and lower surfaces: Smooth, glabrous; semi-glossy. Color: When opening and fully opened, upper surface: Close to 137B. When opening and fully opened, lower surface: Close to 147B.

20

Peduncles.—Length: About 1.5 cm. Diameter: About 1.8 mm. Strength: Moderately strong. Texture and luster: Smooth, glabrous; semi-glossy. Color: Close to 144B.

25

6

Reproductive organs.—Stamens: Quantity per flower: Five. Filament length: About 2.1 cm. Filament color: Close to 155D. Anther length: About 2 mm. Anther shape: Ovate. Anther color: Close to 11D. Pollen amount: Abundant. Pollen color: Close to 11C. Pistils: Quantity per flower: One. Pistil length: About 2.1 cm. Style length: About 1.9 cm. Style color: Close to 144D. Stigma diameter: About 2 mm. Stigma shape: Rounded. Stigma color: Close to 144B. Ovary color: Close to 150B. Fruits: Quantity produced per plant: About 140 during the flowering season. Length: About 3.6 mm. Diameter: About 5.6 mm. Texture: Smooth, glabrous. Color: Close to 161B. Seeds: Quantity per flower: About 35. Length: About 0.5 mm. Diameter: About 0.5 mm. Texture: Smooth, glabrous. Color: Close to 200A.

Garden performance: Plants of the new *Petunia* have been observed to have good garden performance and tolerate wind, rain, temperatures ranging from about 5° C. to about 40° C. and to be suitable for USDA Hardiness Zone 11.

Pathogen & pest resistance: To date, plants of the new *Petunia* have not been observed to be resistant to pathogens and pests common to *Petunia* plants.

25

It is claimed:

1. A new and distinct *Petunia* plant named 'Dopetsurage21' as illustrated and described.
